UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

ART OF COKING COAL IN A RETORTING SPACE.

Application filed July 24, 1922. Serial No. 577,013.

This invention comprehends improvements of especial utility in the coking retort art; and also comprehends certain improvements applicable to coking retort ovens of the well-known Koppers cross regenerative type exemplified in the prior Letters Patent of the United States to H. Koppers No. 818,033, dated April 17, 1906, and in the prior Letters Patent of the United States to Joseph Becker No. 1,374,547 dated April 12, 1921.

The invention has for objects to provide an improved coke oven structure, involving means for introducing steam into the coking retorts or chambers of the battery, the improvements contemplated by the invention providing a maximum yield of blue gas by insuring exceedingly rapid coking of the coal in the lower portion of each retort or coking chamber, with the result that the coking operation in the lower region of the retort is completed in advance of the coking in the upper region of the retort and the lower part of the charge is thus in condition for being steamed in the early part of the coking interval.

In addition to the general objects recited above, the invention has for further objects such other improvements or advantages in construction and operation as are found to obtain in the structures and devices herein-after described or claimed.

In the accompanying drawings, forming a part of this specification and showing, for purposes of exemplification, a preferred form and manner in which the invention may be embodied and practiced, but without limiting the claimed invention to such illustrative instance or instances:

Figure 1 is a vertical section taken transversely through a coking retort oven and partially through a heating wall of the type such as that above specified and equipped with the improvements of the present invention, the view being taken on planes indicated by the line B—B of Fig. 3;

Fig. 2 is a vertical sectional elevation taken longitudinally of the oven battery on the plane indicated by the line A—A of Fig. 1;

Fig. 3 is a horizontal section through the coking chambers or retorts and the contiguous heating walls taken in a plane indicated by the line C—C of Fig. 2; and

Fig. 4 is an enlarged sectional elevation through the steam flow passages and the lower portion of the coking chambers and

heating walls taken in a plane indicated by the line A—A of Fig. 1.

The same characters of reference designate the same parts in each of the several views of the drawings.

In its present embodiment, the invention is incorporated in a coking retort oven or battery having features of the well-known Koppers cross regenerative type exemplified in the patents to H. Koppers and Joseph Becker hereinabove mentioned.

A retort oven or battery of this type includes in its construction crosswise extending parallel heating walls constituted of series of vertical flame or combustion flues, elongated coking chambers or retorts intermediate the heating walls and parallel therewith, and crosswise extending regenerators located at a lower level than the coking chambers and the heating walls and parallel therewith. For convenience, the present description will be confined to this embodiment of the invention; features of construction and operation are, however, capable of other applications; consequently, the invention is not confined in its scope to the specific use and embodiment herein described as an illustrative example.

Referring to the drawings: there are illustrated sectional views of a coke oven battery of the by-product type, such as has been hereinbefore mentioned, which battery embodies

in its construction a plurality of crosswise elongated heating walls 11 and a plurality of intermediate crosswise elongated coking chambers or retorts 12. The heating walls 11 form the side walls of the respective coking chambers 12, as shown more particularly in Fig. 2, and in accordance with the invention, the sides of the coking chambers 12 converge or taper inwardly toward the longitudinal central planes of such chambers and toward the bottoms of the coking chambers, with the result that the several coking chambers are narrower in their lower portions than in their upper portions and the heating walls, together with their flues, are wider in their lower portions than in their upper portions.

The purpose of this construction will appear hereinafter. In the present instance, the heating walls 11 are directly supported by the heavy supporting or pillar walls 13 which extend crosswise of the battery and are located beneath the respective heating walls 11. These pillar walls together with other walls, collectively form the main

support of the entire superstructure of the oven battery and are themselves supported upon a flat mat or platform which constitutes the sub-foundation on which the entire battery rests. The other walls 22 extend directly beneath the respective coking chambers in parallelism between each two adjacent pillar walls 13 and such supporting walls 22 provide two regenerators located on the opposite sides of such walls 22 and between adjacent pillar walls 13. As stated before, the several walls 22 also have the function with the pillar walls 13 of supporting the weight of the battery superstructure.

15 The coal to be coked is charged into the several coking chambers or ovens through charging holes 14 located in the top 15 of the oven battery and positioned directly above the retorts or chambers 12, is shown in Fig. 1. 20 These charging holes 14 are equipped with the usual removable covers (not shown) which are removed during charging of the individual chambers or retorts and are placed in position to close the tops of such retorts 25 during the entire coking or distilling operation. The gases of distillation pass from the tops of the several retorts 12 through gas outlets 16 and thence through ascension pipes (not shown) to the usual gas collecting main 30 which carries the distillation products to the by-product recovery apparatus.

Heat for coking the charges of coal in the several ovens or retorts 12 is derived from the heating walls 11, which, as above mentioned, extend crosswise of the battery at the sides of the coking chambers. Referring now more particularly to Figs. 2 and 3, each heating wall is constituted of a plurality of vertical flame or combustion flues 17. The flame flues of each heating wall are, in accordance with the present embodiment of the invention, operatively disposed into a single group, that is to say—all of the flues of each heating wall operate concurrently as upflow or downflow flues, and, when the flame flues on one side of the coking chamber are burning or operating for upflow, the flame flues on the opposite side of the same coking chamber are operating for downflow to permit exhaust of the waste gases.

50 The crosswise regenerators 18 of the retort oven or battery are located at a lower level than the aforesaid heating walls 11 and coking chambers 12 and extend in parallelism between the pillar walls 13 and the other supporting walls 22. Located in the middle lengthwise vertical plane of the coke oven battery is a vertical partition 19, as shown in Fig. 1, which partition extends all the way up from the mat of the battery to the bottom of the overlying coking chambers and from one to the other of the walls 13 and 22. The regenerators, which are respectively located on opposite sides of the battery extend inwardly to said partition 19 and are separated

thereby, as clearly shown in Fig. 1. Preferably each regenerator is divided into an inner and outer compartment by a vertical partition 109 located between the aforesaid partition 19 and the side of the battery. The partitions 109 however do not extend clear up to the bottom of the coking chamber overlying the regenerator. Each regenerator 18 is a chamber containing open brickwork, commonly called checkerwork, and indicated at 20 with a distributing sole channel 21 underneath and opening up into such checkerwork. The regenerators are heated, in alternation, by the hot combustion products that are exhausted from the flame or combustion flues and then 80 impart such heat to the medium that they feed into those flame flues. The regenerators are grouped into pairs K and L, as shown in Fig. 2, the regenerators of the pairs K alternating with the regenerators of the pairs L. 85 Each pair of such regenerators is provided with a series of ducts 23 all of which lead respectively to individual flame flues 17 of the same heating wall. With this construction, each flame flue 17 communicates by a 90 pair of ducts 23 with adjacent separate regenerators through which flow is maintained concurrently in the same direction. When the regenerators of the pairs K and their communicably connected flame flues are operating for inflow, the regenerators of the alternate pairs L and their communicably connected flame flues are operating for outflow to 95 permit exhaust of the waste gases.

Each flame flue 17 has at its top a port or opening 24 for draft and the passage of combustion products or waste gas from the flame in the flue. These ports 24 open up into horizontal or bus flues 25 formed in the heating walls and connecting all of the vertical flues that communicate with such horizontal flues 25 by means of the ports 24. According to the present embodiment of the invention, the horizontal flues 25 of each heating wall are communicably connected by means 105 of crossover passageways 26 respectively with the corresponding horizontal flue of one of the next adjacent heating walls. Thus the entire flow from the heating wall, within the flues of which combustion is being maintained, passes downwardly through all of the flues of the next adjacent heating wall and each reversal operation is accompanied by a reversal in direction of flow of all the flues of each heating wall.

110 The draft through the ports 24 may be regulated by means of the usual dampers or sliding bricks 27, positioned in the ordinary way in the bottoms of the horizontal flues 25 and adapted to be reached by access flues 28 115 which extend from the top of the horizontal flues 25 in each heating wall to the top 15 of the battery, there being an access flue positioned over each flame or combustion flue of each heating wall.

Extending crosswise of the battery in the pillar walls 13 and located beneath the heating walls 11 thereabove are gas supply channels 29 for the purpose of supplying coke oven gas to the several flame flues. The channels 29 respectively communicate with the individual flues 17 by means of ducts 31 that lead from such channels 29 individually into the bottoms of individual flues. Within the several ducts are disposed the usual nozzles 32. It will be understood that the battery may be operated alternatively with the use of a special generator gas, such as producer gas, as the fuel. During such producer gas operation, one regenerator of each pair of inflow regenerators may be optionally connected with a producer gas main by mechanism such as is disclosed in the prior Letters Patent of the United States of Joseph Becker No. 2,141,632, dated May 16, 1922.

In accordance with the present invention, the soles or bottoms 33 of the several coking chambers or retorts 12 are respectively provided with channels 34. The several channels 34 extend longitudinally of the coking chambers and from side to side of the battery and constitute steam flow passages located directly beneath the bottoms of the retorts. Steam may be introduced into said channels 34 through vertical steam supply pipes 35 located, as shown in Fig. 1 at the end of the heating walls 11 and respectively communicating, at their lower ends, with the horizontal channels 34 by horizontal ducts 36, as shown in Fig. 3. The vertical channels 35 respectively extend to the top 15 of the battery and may, at this point, be connected with any suitable source of steam supply. Inasmuch as said channels 35 are located in the heating walls 11, they function as superheating passages in which the steam introduced from the top of the battery may be superheated to a high temperature before it flows into the horizontal distributing channels 34. From each distributing channel 34 the steam may pass through a great number of distributing ports 37 into the lower relatively restricted or narrower portion of the corresponding coking chamber. The ports 37 provide an extremely diffuse distribution of the steam flow into the corresponding coking chamber. The opposite ends of the horizontal passages 34 may be closed by plugs 38, which are removable at will when it is desired to clean out any of the steam flow spaces.

In the carbonization process, the coking of the coal proceeds inwardly from the opposite sides of the charge of coal in each coking chamber, with the result that the center or core of the charge remains in a more or less gumlike or sticky consistency until the charge is completely coked. Inasmuch as the heating walls 11 and their flues 17 are relatively wider in their lower portion than in their upper portion, and the contiguous cok-

ing chambers are relatively narrower in their lower portion than in their upper portion, the coking of the lower portion of each charge of coal will proceed more rapidly in the lower portion of the charge than in the top of the charge and the lower part of the charge will be completely coked in advance of the upper portion of the charge. Consequently, the lower portion of the charge becomes quickly available for the introduction of steam, the steaming being only effectual for producing blue gas by the water gas reaction when the coking is about complete, and a maximum yield of blue gas will thus be obtained. Narrowing the lower part of the coal charge not only shortens the coking time, but shortens it proportionately more than the narrowing reduces the charge, because narrowing the charge increases the average coking rate. This condition is augmented by increasing the width of the flame flues to provide proportionately more heat to the narrower coke charge. Moreover, although the lower portion of each charge is done in advance of the upper portion, overheating of the lower portion of the charge will be avoided on account of the steam which is introduced into the lower portion of the charge and keeps its temperature below that which tends to cause destruction of the coke. The invention therefore combines extremely rapid coking with a maximum production of gas and yet avoids any overcooking of the charge.

The apparatus herein disclosed is the subject of my co-pending divisional application, Serial No. 230,060, filed October 31, 1927, for coking retort oven. The invention as hereinabove set forth is embodied in a particular form of construction but may be variously embodied within the scope of the claims hereinafter made.

I claim:

1. The improvement in the art of coking coal in a retorting space which consists in forming a vertically and horizontally extended mass of coal having the lower portion thinner than the upper portion and applying extraneously developed coking heat to the sides of such mass during the coking thereof so that the coking of the lower portion of the mass is accelerated and shortened relatively to the upper portion and the lower portion of the mass is completely coked before the upper portion, and, when the coking of the lower portion of the mass is substantially complete, introducing steam into such lower portion until the upper portion of the charge is coked, and thereby increasing the gas production of the charge, while also retarding overcooking of the lower portion thereof; substantially as specified.

2. The improvement in the art of coking coal in a retorting space which consists in applying extraneously developed coking heat to a mass of coal having the lower portion

thinner than the upper portion so that during the coking thereof the coking of the lower portion of the mass is accelerated and shortened relatively to the upper portion and the 5 lower portion of the mass is completely coked before the upper portion, and, when the coking of the lower portion of the mass is substantially complete, introducing steam into such lower portion, and thereby increasing 10 the gas production of the charge, while also retarding overcoking of the lower portion thereof; substantially as specified.

3. The improvement in the art of coking coal in a retorting space which consists in 15 applying extraneously developed heat to a mass of coal having one part thinner than the other so that during the coking thereof the coking of the thinner part of the mass is accelerated and shortened relatively to the 20 other part and the thinner part of the mass is completely coked before the other part, when the coking of the thinner part of the mass is substantially complete, introducing steam

into such completely coked part until the other part of the charge is coked, and thereby 25 increasing the gas production of the charge, while also retarding overcoking of the thinner part thereof; substantially as specified.

4. The improvement in the art of coking coal in a retorting space which consists in 30 applying extraneously developed heat to a mass of coal so that during the coking thereof of the coking of one part of the mass is accelerated and shortened relatively to the other part and one part of the mass may be 35 completely coked before the other part, and, when the one part has attained a temperature at which steam will be dissociated, introducing steam into such one part, and thereby increasing the gas production of the 40 charge, while also retarding overcoking of the one part thereof; substantially as specified.

In testimony whereof I have hereunto set my hand.

JOSEPH BECKER.

CERTIFICATE OF CORRECTION.

Patent No. 1,707,427.

Granted April 2, 1929, to

JOSEPH BECKER.

It is hereby certified that error appears in the printed specification of the above numbered patent requiring correction as follows: Page 4, line 21, claim 3, after the comma that follows the word "part" and before the word "when" insert the word and comma "and,;" and that the said Letters Patent should be read with this correction therein that the same may conform to the record of the case in the Patent Office.

Signed and sealed this 18th day of June, A. D. 1929.
